(57) **CLAIM**

The ornamental design for a necktie, as shown and described.

DESCRIPTION

FIG. 1 is a front view of a necktie of my present invention having two upper sections that are fastened to provide a loop, showing the necktie as it appears before the upper sections are fastened around the neck of an individual; FIG. 2 is a front view of the necktie of FIG. 1 showing the necktie as it appears after the upper sections are fastened to provide the loop;

FIG. 3 is a second front view of the necktie of FIG. 1; FIG. 4 is a side view of the necktie of FIG. 1, the opposite side is essentially the same; and,

FIG. 5 is a rear view of the tie of FIG. 3.
